(57) **CLAIM**

The ornamental design for a tool head, as shown and described.

DESCRIPTION

FIG. 1 is a perspective view of a tool head showing my new design;

FIG. 2 is a front view thereof, with the opposite side being a mirror image thereof;

FIG. 3 is a left view thereof;

FIG. 4 is a right view thereof;

FIG. 5 is a top view thereof; and,

FIG. 6 is a bottom view thereof.

The broken lines shown in the drawings illustrating portions of a tool are included to demonstrate environmental structures and form no part of the claimed design.
